CARBURETOR WITH STATIONARY METERING PIN

Andrew Craig Russell, Shawnee, Okla.

Application October 18, 1952, Serial No. 315,542

1 Claim. (Cl. 261—50)

This invention relates to carburetors particularly adapted for use with internal combustion engines to admix air and fuel, such as gasoline, atomize the latter and direct the admixture to the engine, the primary object being to improve upon the carburetor forming the subject matter of my co-pending application, Serial No. 41,933, filed August 2, 1948, now Patent No. 2,614,581, this being a continuation-in-part thereof.

In my said co-pending application, as well as in my related Patents 2,366,056; 2,506,812; 2,529,665; and 2,536,700, carburetors are provided which have a metering pin reciprocable within a stationary bore and operably coupled with an air valve for reciprocation thereby as the air valve in turn moves through a vertical, rectilinear path of travel. In said application and said patents, as well as in my Patent No. 2,536,889, the vertically reciprocable air valve is mounted on a stationary tube for reciprocation with respect thereto.

It has been found that such principles can be improved upon to a great advantage by eliminating chatter and "dancing" of the metering pin as a consequence primarily of vibration and shaking as the automobile, with which the carburetor is used, passes over rough terrain.

It is the primary object of the present invention therefore, to provide a carburetor having a stationary metering pin within the fuel bowl thereof, together with a tube through which the fuel-air admixture passes, fittable over the metering pin and reciprocable with respect thereto whereby to admit varied quantities of fuel in direct proportion to the requirements of the internal combustion engine.

Another object hereof is to provide a carburetor as above set forth that includes a vertically reciprocable air valve as above mentioned which is directly connected with the reciprocable tube for reciprocating the latter and thereby admit progressively greater amounts of fuel to the tube as the air valve rises to admit additional air in response to changing pressures within the intake manifold of the internal combustion engine.

Other objects include important details of construction, all of which will be made clear as the following specification progresses, reference being had to the accompanying drawing, wherein:

Figure 1 is a substantially central, cross-sectional view taken through a carburetor having a stationary metering pin made pursuant to my present invention; and

Fig. 2 is a fragmentary, cross-sectional view taken on line II-II of Fig. 1.

Reference may be had to my prior patents above identified and particularly to Patent No. 2,366,056, for a complete understanding of the basic principles of operation of a carburetor such as forms the subject matter hereof.

As in my aforementioned prior disclosures, there is provided a hollow housing broadly designated by the numeral 10, having an air inlet opening 12, an outlet 14 to the intake manifold not shown, of an internal combustion engine and a continuous passage therethrough

2

interconnecting the inlet 12 and the outlet 14 and broadly designated by the numeral 16.

A fuel bowl 18 is removably mounted on the bottom wall 20 of housing 10 and is placed in communication with a source of raw fuel such as gasoline, not shown, by a line 22, having a valve 24 therein that is in turn controlled by a float 26 within the fuel bowl 18.

A tubular member 28 has a pair of spaced, outturned flanges 30 and 32 within the fuel bowl 18, the former being in underlying engagement with the bottom wall 20 and secured thereto in any suitable manner such as by bolts 34. The member 28 has a continuous, vertical bore 36 therethrough placing the fuel bowl 18 into communication with the passage 16. A length 38 of reduced diameter forming an integral part of the member 28 extends upwardly through an opening 40 in the wall 20 and is provided with external threads 42 within the passage 16. A nut 44 on the threaded length 38, cooperates with a ring-like air valve 46 which it is adapted to support in closing the passage 16 when the valve 46 is resting on the nut 44 as shown in the drawing. The nut 44 is rotated and therefore, raised and lowered toward and away from the bottom wall 20 by means of a pin 48 having a worm 50 in mesh with external threads 52 on the nut 44. The bore 36 of member 28 is placed in communication with the passage 16 by a plurality of downwardly and inwardly inclined passages 54, the nut 44 having a cavity 56 for clearing the uppermost ends of the passages 54.

30 A plurality of rods 58 passing through the bottom wall 20 and the flanges 30 and 32 for reciprocable movement therein, are joined at the lowermost ends thereof by plate 60 within the fuel bowl 18, and are connected to the valve 46 at their uppermost ends. An opening 35 62 in the plate 60 clears a vertically reciprocable tube 64 within the bore 36 terminating at its lowermost end within the fuel bowl 18 and at its uppermost end above the valve 46 and below the outlet opening 14.

40 A rigid, tapered metering pin 66 secured directly to the bottom wall of the fuel bowl 18 and extending upwardly therefrom, projects into the tube 64 at the lowermost end of the latter. The tube 64 is provided with a wall 68 therewithin that may be either integral therewith or in the form of a press-fit plug disposed above the uppermost end of the pin 66 and having a vertical perforation 70. Additionally, tube 64 has an elongated, vertical slot 72 immediately above the wall 68 in register with each inclined passage 54 respectively, which slots 72 and passages 54 remain in registration at all times during reciprocable movement of the tube 64. Tube 64 is secured directly to the valve 46 for reciprocation thereby through the medium of a cross plate 74 secured to the valve 46 and to the tube 64. A choke valve 76 is provided in the passage 16 adjacent the inlet opening 12 and an auxiliary valve 78 normally spring-loaded to the closed position shown in Fig. 1 is adapted to admit air into the passage 16 when valve 76 is closed in response to decreased pressure within the passage 16 between the valves 76 and the outlet opening 14.

60 It is seen that air is admitted from the passage 16 into the tube 64 by way of passages 54 and slots 72 to impinge upon the level of liquid fuel within the tube 64 above the wall 68. Reduced pressure at the uppermost end of the tube 64 as a result of suction created by the intake manifold of the internal combustion engine, moves the air and fuel admixture upwardly from the wall 68 through the tube 64 and through the outlet opening 14 to the engine. More or less fuel is admitted to the tube 64 and more or less air flows through the passage 16 as the extent of suction by the intake manifold varies, since increased suction reduces the pressure above the

valve 46 and raises the same from its supported position on the nut 44.

Manifestly, such upward movement of the valve 46 permits more air to flow through the passage 16 from inlet 12 to outlet 14 and simultaneously permits more raw fuel in the fuel bowl 18 to enter the tube 64 around the metering pin 66. Raising and lowering of the nut 44 by manipulation of pin 48, provides adjustment for idling purposes in the same manner as fully described in my aforementioned patents.

It is now seen that for the first time there is provided a vertically reciprocable tube 64 that cooperates with a stationary pin 66, which tube 64 is motivated simultaneously with the valve 46 and by the latter because of the direct connection between tube 64 and the valve 46 through the plate 76. Tests have proved that these improvements which eliminate chattering and "dancing" of the pin 66 within the fuel bowl 18, obviate any tendency to constantly flood the engine with jets of raw fuel as is the tendency when the metering valve is floatingly mounted or permitted to reciprocate as in my aforesaid disclosures. Elimination of the bursts of unneeded raw fuel as a consequence of movement of a vehicle with which the carburetor is used, provides for smoother operation and reduces gas consumption, and while changes may be made from the details of construction hereinabove described, it is desired to be limited only by the spirit of the invention as defined by the scope of the appended claim.

Having thus described the invention what is claimed as new and desired to be secured by Letters Patent is:

In a carburetor; a housing having an air inlet, an outlet, and a passage therethrough, said passage including an intermediate, circular aperture having a vertical axis; a hollow fuel bowl mounted on said housing and therebelow, said bowl vertically underlying said aperture of the passage; a plurality of elongated, vertical rods mounted in the housing for vertical reciprocation relative thereto, the lowermost ends of said rods being disposed

within said bowl and the uppermost ends thereof being disposed within said passage and adapted to pass through said aperture when they are vertically reciprocated; valve-supporting structure of circular cross-section mounted on the housing beneath and in axial alignment with said aperture, said structure extending upwardly to said aperture to define an annular opening between the housing and the uppermost extremity of the structure, said structure being provided with a vertical bore therethrough and a lateral passage communicating with said inlet and with said bore intermediate the extremities of the latter; an annular valve within the passage and above said structure, said valve being secured to the uppermost ends of the rods and thereby mounted for vertical reciprocation to and from a seated position resting on said structure and closing said opening; an elongated tube slidably mounted in said bore for vertical reciprocation, the uppermost extremity of the tube extending above the structure and through the valve into communication with said outlet, the lowermost end of the tube extending through the structure and the housing into the bowl, said tube being provided with an elongated, vertical slot in communication with said lateral passage regardless of the reciprocated position of the tube; a plate interconnecting the lowermost ends of the rods within the bowl and provided with an opening clearing the tube; a cross-plate within the passage and above the aperture interconnecting the tube with the valve; and an upright, tapered, metering pin rigidly mounted on the bowl and extending upwardly therewithin into a lowermost portion of said tube.
